Chester H. Braselton
ATTORNEY.

UNITED STATES PATENT OFFICE.

ARTHUR J. BAKER, OF TOLEDO, OHIO, ASSIGNOR TO THE WILLYS-OVERLAND COMPANY, OF TOLEDO, OHIO, A CORPORATION OF OHIO.

ENGINE MOUNTING.

Application filed March 12, 1927. Serial No. 174,894.

This invention relates to engine mountings and more particularly to engine mountings such as are used in automobiles.

One of the objects of the invention is to provide an engine mounting that will absorb or cushion the unbalanced forces that arise from the operation of the engine, and thereby prevent their transmission to the vehicle frame.

Another object of the invention is to provide a resilient engine support that may be formed of sheet metal.

Another object of the invention is to provide an engine with frame supporting members of the plate type that will effectively restrain fore and aft movement of the engine.

Further objects involved in the various features of the invention, and apparent from the specific type of mechanism employed, which may be preferred in carrying out the invention, will become evident upon consideration of the detailed description herein-after made and of the accompanying drawings in which:

Figure I is a perspective view of a portion of a vehicle frame with an engine supported thereon in accordance with the principles of my invention.

Fig. II is a detail view of the improved engine supporting member.

Fig. III is a bottom view of the improved support.

Fig. IV is a perspective view of a frame bracket.

Referring to the drawings in which like characters designate like parts throughout the views, 1 is an engine which is supported upon the frame members 2 and 2^A, by the front and rear sheet metal support members

3 and 4 respectively. The support members are secured to opposite ends of the engine 1 by any suitable means such as bolts 5 and are preferably detachable for convenient replacement.

Heretofore it has been usual practice to support both the front and rear of an engine by sheet metal supports having both the central and the projecting portions of the support in the same plane, the construction being similar to that of the front support 3 illustrated in Fig. I. Removable flat supports are desirable because of their low cost, and also because of the ease with which an engine without projections may be handled

during its manufacture. The principal objections to the flat supports which have been used heretofore are their extreme rigidity in the plane of the support, and their flexibility in a direction at right angles to this plane. These characteristics result in the transmission of unbalanced engine forces to the frame, and also permit considerable longitudinal movement of the engine during acceleration and deceleration of the vehicle. The same objections are applicable to both front and rear supports of the flat design but it has been found that for practical purposes, one support of my improved construction is generally sufficient. I prefer to locate the improved support at the rear of the engine because the vibration due to the unbalanced engine forces is more noticeable at this point, although if desired it may be located at the front or even both supports may be of the improved construction. In Fig. I, I have illustrated a preferred embodiment in which the rear support 4 is of the improved type and the front support 3 is of the well known plate type. The middle portion of support 4 is preferably flat for convenient attachment to the rear face of engine 1, and is secured thereto by bolts 5, but the projecting ears 6 are inclined to the central portion at an obtuse angle thereto, the preferable inclination being rearward with respect to the engine, for increasing the distance between the front and rear supports. Ears 6 preferably include horizontal flange portions 7 which afford additional strength, and provide greater contact area for supporting the load.

Inclined brackets 8 and 8^A are secured to the inner sides of the frame members 2 and 2^A respectively, by any suitable means such as rivets 9, the inclination being such as to permit the vertical webs 10 to be contiguous to the inclined ears 6. The brackets 8 and 8^A are preferably provided with horizontal flange portions 11 for permitting the engine to be supported temporarily by the engagement of ears 6 with flanges 11 during the assembly of the vehicle. The rear support 4 is secured to brackets 8 and 8^A by any suitable means such as bolts 12 and the front support is secured at each end in the usual manner, to a frame bracket 13 by means of a bolt 14.

The herein described method of attachment permits the engine to be supported fore and aft with a much greater distance

between the front and rear supports than when the conventional flat plates are used, and the tendency of the engine to rock about a horizontal transverse axis is reduced materially. Furthermore, the unbalanced forces of the engine including the intermittent torque reaction forces, are absorbed to a great extent by the inclined ears 6 before they are transmitted to the side members 2 and 2^A, and are therefore rendered unobjectionable to the vehicle occupants. My improved engine support also materially reduces the longitudinal movement of the engine 1 with respect to the frame members 2 and 2^A, as fore and aft forces arising from stopping and starting the vehicle are resolved into tension or compression components acting upon the ears 6, which, to a great extent, counteract the bending moment 20 acting on the flat front member 4.

While I have illustrated and described somewhat in detail one embodiment of the invention, it is to be understood that this showing and description are illustrative only, and that I do not regard the invention as limited to the details of construction illustrated and described, except in so far as I have included such limitations within the terms of the following claims, in which it is 30 my intention to claim all novelty inherent in the invention broadly as well as specifically.

I claim:

1. In a motor vehicle, the combination of 35 a frame, an engine, a sheet metal support for said engine, said support including a flat central portion secured to said engine, and end portions projecting outwardly from said central portion, said end portions forming obtuse angles with the central portion, and means for securing the end portions to said frame.

2. In a motor vehicle, the combination of 45 a frame having spaced side members, an engine mounted between the side members, a sheet metal support for connecting said engine to said side members, said support including a vertical central portion secured to the engine and projecting end portions, said end portions forming obtuse angles with respect to said central portion, and means for securing said end portions to said frame members.

3. In a motor vehicle, the combination of 55 a frame having spaced side members, an engine mounted between said members, front and rear supports for connecting said engine to said frame members, at least one of said supports having a vertical flat central portion secured to said engine and projecting end portions, said end portions being inclined to the central portion in a manner to increase the distance from the first sup-

port, and means for securing said end portions to said frame. 65

4. In a motor vehicle, the combination of a frame having spaced side members, an engine mounted therebetween, front and rear supports for securing said engine to said members, one of said supports having a central flat portion secured to said engine and end portions projecting beyond said engine, said end portions forming an obtuse angle with respect to said central portion, said end portions comprising a vertical web 70 and a horizontal flange, a bracket secured to each of said side members substantially parallel to the end portion of said support, said bracket having vertical and horizontal portions contiguous to the web and flange 75 of said support, and means for securing said bracket to said support. 80

5. In a motor vehicle, the combination of a frame having spaced side members, an engine mounted therebetween, front and rear supports for securing said engine to said members, one of said supports having a central flat portion secured to said engine, and end portions projecting beyond said engine, said end portions forming an obtuse 85 angle with said central portion, brackets secured to said frame having portions thereof parallel and contiguous to said end portions, and means for securing said brackets to said supports. 95

6. In a motor vehicle, the combination of a frame having spaced side members, an engine mounted between said side members, front and rear supports secured to said engine, said rear support having end portions 100 projecting beyond the central portion, said end portion being inclined rearwardly with respect to the central portion, and means for attaching said end portions to the frame.

7. A sheet metal support for a motor 105 vehicle engine comprising a flat central portion adapted to be secured to a vertical flatted face of an engine, projecting end portions adapted to be secured to a vehicle, and said end portions forming an obtuse 110 angle with said central portion.

8. A sheet metal support for a motor vehicle engine comprising a flat central portion adapted to be secured to a vertical flatted face of an engine, projecting end portions adapted to be secured to a vehicle, said end portions having webs forming obtuse angles with said central portion, and said webs having flanges thereon at their lower edges, the planes of which are at substantially right angles to both the plane of the web and the plane of the central portion. 115 120

In testimony whereof, I affix my signature.

ARTHUR J. BAKER.
